No. 664,534.

Patented Dec. 25, 1900.

T. P. CONNELLY.

BOILER.

(Application filed Apr. 12, 1900.)

(No Model.)

UNITED STATES PATENT OFFICE.

THOMAS P. CONNELLY, OF JERSEY CITY, NEW JERSEY.

BOILER.

SPECIFICATION forming part of Letters Patent No. 664,534, dated December 25, 1900.

Application filed April 12, 1900. Serial No. 12,568. (No model.)

To all whom it may concern:

Be it known that I, THOMAS P. CONNELLY, a citizen of the United States, and a resident of Jersey City, in the county of Hudson and State of New Jersey, have invented a new and Improved Boiler, of which the following is a full, clear, and exact description.

The object of the invention is to provide a new and improved boiler which is simple and durable in construction, provided with a large heating-surface, and arranged to permit of conveniently and quickly removing a defective boiler-tube without disturbing any of the other tubes.

15 The invention consists of novel features and parts and combinations of the same, as will be fully described hereinafter and then pointed out in the claims.

A practical embodiment of the invention 20 is represented in the accompanying drawings, forming a part of this specification, in which similar characters of reference indicate corresponding parts in all the views.

Figure 1 is a sectional side elevation of the 25 improvement. Fig. 2 is an enlarged sectional side elevation of the upper end of one of the tubes in position in the bottom of the steam-compartment. Fig. 3 is a similar view of the lower end of the tube in the top of the water-compartment.

The improved boiler is provided with a suitable fire-box A, surrounded on the sides and top by a water-compartment B, having its top B' connected by water-tubes C with the 35 bottom D' of a steam-compartment D; all enclosed in a shell E, having the usual smoke-outlet F. The throat A' of the fire-box A opens centrally through the top B' of the water-compartment B into a central space 40 formed by the innermost row of tubes C, and a suitable distance above the throat A' is arranged a baffle-plate G, supported by a rod G' from the bottom D' of the steam-compartment D, as is plainly indicated in Fig. 1.

45 The smoke and gases passing from the fire-box A through the throat A' into the said central space are deflected by the baffle-plate G and pass between the tubes C to the shell E and then travel upward until deflected inward by a baffle-plate H in the shape of a frustum of a cone the base of which is secured to the inner surface of the shell E.

The apex end of the baffle-plate H extends close to the outer row of tubes C, so that the rising smoke and gases are forced in an inward direction between the tubes to the central space and under the bottom D', to then pass outward into the space between the steam-compartment D and the shell E, and finally rise to the outlet F.

As illustrated in the drawings, the tubes C are curved, and the top B' and the bottom D' are dished toward each other, the ends of the tubes extending approximately at right angles to the said top and bottom. The openings for the tubes in the top B' correspond to the diameter of the tubes, while the openings in the bottom D' are somewhat larger than the diameters of the tubes, so that when the tubes are inserted in said top and bottom then 70 the upper end of each tube is made bell-shaped, as at C', to fit the tube snugly into the opening in the bottom D'. (See Fig. 2.) The lower end C² of each tube is projected beyond the under side of the top B' and is 75 then flanged outward, as is plainly shown in Fig. 3, to securely hold the tube in place.

The curvature given to the tubes C is such that when a tube is loosened at its lower end C² then the operator can slide the tube upward through the steam-compartment D and through the manhole D² therein, whereby the tube can be conveniently removed from the boiler in case it becomes defective, it being understood that all that is necessary to loosen 80 the tube is simply for the operator to enter the water-compartment B (when empty) through the manhole B² and to press the flange C² back into circular shape, after which the tube can be moved upward through the steam-compartment and a new tube can be inserted, 85 if necessary.

As illustrated in Fig. 1, four circular concentric rows of tubes C are shown; but it is evident that a greater or lesser number of 90 rows may be employed, if deemed necessary, and the outermost tubes may be moved directly without sliding the same through the compartment D upon first removing the shell to give access to the outermost row of tubes. 95

It is understood that the water readily circulates from the water-compartment B through the tubes C into the lower portion of the steam-compartment D, and the steam is 100

taken from the steam-compartment in the usual manner.

Having thus fully described my invention, I claim as new and desire to secure by Letters Patent—

1. A boiler having steam and water compartments, and tubes connecting the same with each other, said tubes being curved and the bottom of said steam-compartment and 10 the top of said water-compartment being dished toward each other, the ends of the curved tubes being approximately at right angles to said top and bottom, as set forth.

2. A boiler comprising a steam-compartment, having a manhole in its top, a water-compartment, and tubes connecting said compartments with each other, said tubes being curved to permit of removing the tubes through the manhole in the top of the steam- 20 compartment, substantially as shown and described.

3. A boiler having a steam-compartment provided with a manhole in its top, a water-compartment, and tubes connecting said compartments with each other said tubes being curved to permit of removing the tubes through the manhole, the bottom of said steam-compartment and the top of said water-compartment being dished toward each 30 other and the end of the tubes extending approximately at right angles to said top and bottom, and baffle-plates for deflecting the smoke and gases, substantially as set forth.

4. A boiler having a steam-compartment, a 35 water-compartment, and tubes connecting said compartments with each other, said tubes being curved to permit of removing the tubes through a manhole in the top or the steam-compartment, the tube-opening in the bottom of the steam-compartment being some-

what larger than the tube-opening in the top of said water-compartment, to permit of readily removing a loosened tube as above described.

5. A boiler, comprising a fire-box, a water-compartment surrounding the fire-box, a steam-compartment, tubes connecting the compartments with each other and arranged in concentric circular rows to form a central space into which opens the fire-box, a boiler-shell surrounding said tubes and steam-compartment and forming an outer space with the same, a baffle-plate in the central space above the throat of the fire-box, and a baffle-plate in the form of a frustum of a cone, and 50 secured with its base to the shell above said central baffle-plate, substantially as shown and described.

6. A boiler, comprising a fire-box, a water-compartment surrounding the fire-box, a steam-compartment, tubes connecting the compartments with each other and arranged in concentric circular rows to form a central space into which opens the fire-box, a boiler-shell surrounding said tubes and steam-compartment and forming an outer space with the same, a baffle-plate in the central space above the throat of the fire-box, and a baffle-plate in the form of a frustum of a cone and 65 secured with its base to the shell above said central baffle-plate, the apex end of said cone-shaped baffle-plate reaching to the outermost row of tubes, as set forth.

In testimony whereof I have signed my name to this specification in the presence of 75 two subscribing witnesses.

THOMAS P. CONNELLY.
